UNITED STATES PATENT OFFICE.

OTIS A. MYGATT, OF NEW YORK, N. Y.

DESIGN FOR A SHADE, REFLECTOR, OR SIMILAR ARTICLE.

46,290.

Specification for Design.

Patented Aug. 18, 1914.

Application filed June 5, 1908. Serial No. 437,003. Term of patent 14 years.

To all whom it may concern:

Be it known that I, OTIS A. MYGATT, a citizen of the United States, residing at New York, in the county of New York and State of New York, have invented a new, original, and ornamental Design for Shades, Reflectors, or Similar Articles, of which the following is a specification, reference being had to the accompanying drawing, forming part thereof.

In the drawing is shown a bottom perspective of a shade or reflector embodying my invention.

My design is applied to glass shades or reflectors which are circular in plan, and consists in providing the same with a lower

cylindrical skirt portion having protuberances upon the inner and outer surfaces thereof, substantially as shown in the drawing.

I claim—

The ornamental design for a glass shade or reflector having a circular plan which consists in providing the same with a lower cylindrical skirt portion having protuberances upon the inner and outer surfaces thereof, substantially as shown.

OTIS A. MYGATT.
